UNITED STATES PATENT OFFICE.

JOSEPH L. LOWRY, OF PITTSBURG, PENNSYLVANIA.

IMPROVEMENT IN THE MANUFACTURE OF STOP-COCKS.

Specification forming part of Letters Patent No. 44,326, dated September 20, 1864.

To all whom it may concern:

Be it known that I, JOSEPH L. LOWRY, of the city of Pittsburg, in the county of Allegheny and State of Pennsylvania, have invented a new and useful Improvement in Stop-Cocks; and I hereby declare that the following is a full, clear, and exact description thereof, reference being had to the accompanying drawings, forming a part of this specification, and to the letters of reference marked thereon.

My invention relates to an improvement in the construction of that class of stop-cocks used for shutting off the flow of water in "street-mains," or pipes used for conveying water through the streets of cities, and for other purposes; and it consists in forming a stop cock of cast-iron, with brass-faced iron valves and valve-seats therein in such a manner as to obviate the necessity of "fitting," and at the same time make a better and more perfect job, which I accomplish by first casting the rings for facing the valves and valve-seats of composition or brass, with a "dovetail" projection thereon, and then placing them, when so cast, in the mold wherein the molten iron is to be poured, which, as it comes in contact with the dovetail projection on the facings of the valve and valve-seats, partially fuses the same and unites them with the iron forming the body of the stop-cock in a cheap, durable, and effective manner.

My lifting-screw, Figure 5, is made by taking a round bar of wrought or other iron of sufficient length and thickness and passing it through a screw-cutting machine for the purpose of cutting a thread on it and taking the scale off. The rod or bar is then heated, but not so hot as to raise a scale. It is then placed in the mold and the brass or composition cast round it. Previous to the rod being placed in the flask or mold it is dusted with borax or other material that will assist in fusing the iron and composition. The iron is heated, so as not to chill the composition or brass and the more readily fuse with it, and in cooling shrink with the composition or brass. The object in cutting a thread or recess on the iron bar is to give additional surface for the composition to fuse with the iron, and in case that the composition should fail to fuse with the iron it will be so interlaced with the iron by threads or recesses interlocking each other that the composition cannot be stripped off the iron rod or

screw. The dovetails on the rings for facing the valve and valve-seat are to give additional surface for the two metals to unite or fuse. Should the metals fail to fuse, the dovetail being interlocked, the brass ring or face is secured to the iron in the valve or valve-seat.

To enable others skilled in the art to understand and make my invention, I will proceed to describe its construction by reference to the accompanying drawings, in which—

Fig. 1 represents a side elevation of a stop-cock. Fig. 2 is a transverse vertical section of the same. Fig. 3 represents two stop-cocks attached to a cross-pipe. Fig. 4 is an enlarged vertical section of a four-way cock, with "fire-hydrant" attached. The brass face of the valve-seat, being toward the interior of the stop-cock, cannot be seen, but the brass face of the valve is seen, a part of the stop-cock chamber being cut away for that purpose. A part of the brass ring or valve-face being cut away, so as to show the manner the brass face C is united to the cast-iron of the valve. Fig. 5 represents a transverse vertical section of the lifting-screw. Fig. 6 represents a section of a disk, showing the old method of attaching the brass face to the iron for a valve. Fig. 7 represents the same with my improved method of securing the brass face to the valve. Fig. 8 represents a ring or valve-seat having the brass attached according to my plan, part of which is broken away to show the dovetail.

All the drawings are lettered, and similar letters indicate like parts on all the figures.

The brass or composition rings or valve-facings C and facings for the valve seats C', having been cast with the dovetail R, the scale is taken off by scraping or pickeling, a proper recess having been made in the cock-pattern for the reception of the dovetail, so that the brass can lay close. The pattern and ring are then placed in a flask and the sand rammed around the pattern, as for other work. The flask being opened and the pattern taken out, the "gates" are cut, so as to prevent as much as possible the current of metal (which in temperature is four times greater than molten brass) from cutting or washing away the rings. Previous, however, to closing the flask for the purpose of casting the iron care must be taken that no sand is left on that part of the brass rings intended to unite with the iron, but must be dusted over with borax or any other sub-

stance that will flux and assist the fusion and welding of the dovetail on the rings to the iron in the valve and valve-seat. The mold being closed, the iron should not be poured in too hot, but time should be given to enable it to cool to that degree that it will barely flow into the mold, using for that purpose soft gray iron with open pores, the heat of the iron being graduated—that is, raised or lowered, as the composition of brass is hard or soft—when brass and iron will be found perfectly united.

The body of the cock being in other respects similar to the ordinary cocks used for this purpose, a description thereof is herein

deemed unnecessary, as its construction and operation are fully set forth in my application for a patent filed May 13, 1863, and patented January 5, 1864.

Having thus described my invention, I claim—

Constructing the valve, valve-seat, and lifting screw of stop-cocks in the manner and by processes and means substantially as described.

JOSEPH L. LOWRY.
